UNITED STATES PATENT OFFICE

2,000,402

CABINET

Frank J. Matchette, New York, N. Y., assignor
to The Servidor Company, New York, N. Y., a
corporation of Delaware

Application August 12, 1932, Serial No. 628,515

3 Claims. (Cl. 312—152)

This invention relates to a cabinet adapted to be hingedly mounted upon a bathroom door, to form therewith a convenience closet for storing such bathroom necessities as are required in daily use.

Apartments and small homes seldom have sufficient closet space in the bathroom, and the cabinet of the instant invention affords a practical way of overcoming this shortage.

10 In my co-pending application, Serial No. 485,873, filed October 2, 1930, there is disclosed a cabinet, which is adapted to be mounted upon a bathroom door to form a closet for that room. Broadly speaking, the instant application is an improvement upon this co-pending application.

In its preferred form, the cabinet of the present invention is a generally rectangular structure having an open face adapted to be registered with the bathroom door. The structure is adapted to be hung for either right or left swinging movement on the door, and is provided with a suitable latch which retains it in closed position on the door.

Within the cabinet I have provided a plurality of shelves adapted to receive the articles of bathroom equipment which are too large to conveniently fit into the medicine case of the room, and a plurality of hooks from which can be hung such articles as hot water bags, razor strops, etc. I have also provided a hamper for soiled linen.

The cabinet thus formed, when installed upon a bathroom door, converts what is otherwise waste space into a convenient closet wherein the unsightly requisites of a bathroom can be stored.

35 My invention will be best understood by reference to the accompanying drawing, in which a preferred embodiment of it is shown by way of example and in which:

Figure 1 is an elevational view of the cabinet attached to a door and opened away therefrom;

Figure 2 is a cross-sectional view of Figure 1 taken substantially along the line 2—2 looking in the direction of the arrows;

Figure 3 is a cross-sectional view taken along the line 3—3 of Figure 2, looking in the direction of the arrows and drawn to an enlarged scale to show the details of construction;

Figure 4 is a perspective view of the spring catch and striker plate therefor;

50 Figure 5 is a perspective view of a hook; and

Figure 6 is a perspective view of the door stop assembly.

Referring now to the drawing in more detail, the door, indicated generally at 1, and upon which the cabinet of my invention is adapted to be

mounted, comprises, side stiles 2 and 3, which are connected together by suitable top and bottom rails 4 to form a frame for the panel or panels 5.

The shell or body structure of the cabinet of my invention comprises angle members 6 which have one leg adapted to engage the stiles of the door, and have another leg adapted to be disposed at right angles to the door. The stile engaging legs of the structure are pierced with a plurality of holes 7 through which mounting screws are projected to mount the hinge 8 thereupon. Both angle members 6 are so pierced so that the hinges may be mounted upon either one of them to thereby permit mounting hinges either upon the right, or the left side of the cabinet.

Formed integrally with the free edges of the second ones of the legs of said angles, are side pieces 10, disposed at an acute angle to the door and extending towards the central portion thereof. The free edges of these side pieces 10 are formed integral with the planar front panel member 11, which is disposed substantially parallel to the panel 5 of the door.

The top plate 12 is registered with the angles 6, side pieces 10 and panel 11, and contains flanges by which it is fixed thereto, preferably by welding. This top plate 12 is pierced with two holes 14, one located near each end of the plate. These holes are adapted to receive a pin by which a suitable door stop is fixed to the cabinet to limit the movement of the cabinet with respect to the door. A similar bottom plate 15, having flanges 16 registered with the angles, side pieces and panel of the door is fixed in the opposite end of the cabinet to close the same. The bottom 15 is not ordinarily provided with holes, since the door stop is mounted at the top rather than at the bottom of the cabinet.

The precise dimensions of the structure thus formed will be varied to fit various sizes of doors. In all instances, however, the angles 6 will be spaced far enough apart to permit them to overhang the side stiles of the door, and the cabinet structure will be long enough to overhang the top and bottom rails of the door. Preferably, the cabinet is approximately seven inches narrower than the width of the door, so that there is a margin of three and one-half inches upon each side of the cabinet when it is secured to the door. This margin is ample to permit the door knob to be operated with ease, particularly since the edges of the cabinet adjacent the door knob are tapered to increase the working room. The

length of the cabinet is preferably several inches shorter than the door, so that, when the cabinet is installed upon the door it is disposed at some distance above the floor of the room. This permits the floor under the cabinet to be easily cleaned with an ordinary broom or mop.

The thickness of the cabinet is preferably approximately the same as the width or thickness of the door frame. Thus when the cabinet is mounted 10 on the side of the door swinging into the frame when the door is closed, the cabinet fits within the door frame and occupies only what is otherwise waste space. In certain instances, where a door is mounted to swing through ninety 15 degrees into parallel relation with a wall, having the cabinet of a thickness equal to the thickness of the frame of the door permits the door to be fully opened before the cabinet strikes against the wall. The tapered edges of the cabinet, in 20 either event, permit its installation upon the door and operation thereon without striking against the door frame.

In the embodiment shown sheet metal is used 25 in the construction of this shell or body of the cabinet. While this material is preferable, because of its great strength and relatively low cost, I am not to be limited to cabinets constructed in this manner, as I contemplate employing wood, or the composition building material commercially known as "Presswood". The 30 cabinet may be finished to match the finish of the room in which it is installed, or to match the door upon which it is mounted.

The second legs of the angles 6, that is to say, the legs disposed normal to the door, are pierced 35 with holes 17 to permit mounting a latch member 18 thereupon. This latch member comprises a mounting escutcheon 19 containing holes through which suitable bolts are projected to attach it to the angle member 6. Ears 20 are turned up out of this escutcheon to receive a pivot pin 21 upon which the movable member 22 of the latch is pivotally mounted. This movable member contains parallel arms 23 which are 40 formed with hooks at their free ends, and a handle 24, by which the member is rotated upon its pivot. A spring 25, wound around the pivot pin 21 and engaging the escutcheon and the movable member, restores the movable member to its normal position when the handle is released.

A striker plate mounted upon the door stile 45 contains a keeper 27 which is engaged by the hooked ends of the arms 23 of the movable member to secure the cabinet structure in closed position upon the door. Inasmuch as both of the stiles of the cabinet are pierced with mounting holes, obviously the latch 18 may be mounted upon either side of the cabinet. The particular design of the latch may be varied within the 50 teachings of my invention.

Within the cabinet I have disposed a plurality 55 of shelves 35, the upper two of which are low shelves, that is to say, these shelves are placed relatively close together and are adapted to receive objects which do not project a great distance above the shelves. The two lower shelves are so-called high shelves adapted to receive taller articles.

Each of these shelves comprises a flat, planar 60 portion disposed in horizontal position and flanged at its front and back edges. The back edge flange 36 is disposed against the panel member 6 and attached thereto in any suitable manner, such as by spot-welding. The front flange 37 of the shelves extends upwardly from the shelf and

serves as an edge for preventing small articles from rolling or sliding off of the shelf.

In order to eliminate the possibility of tall 5 articles placed upon the high shelves from tipping over and falling off of the shelves as the cabinet is opened upon hinges 8, I have provided guard bars 38 which are disposed a short distance above the shelf and securely fixed to the flanges 6 of the cabinet.

Upon the flange 36 of the lower shelf 35, I have 10 mounted a plurality of hooks 39 which are adapted to receive such articles as hot water bottles and the like. A second row of hooks 39' are attached to the panel 11 a short distance below the hooks 39. Each one of the hooks 39 15 is formed from a short piece of wire of suitable gauge and flattened at one end to afford a flat seat which is welded to the supporting member.

At the bottom of the cabinet I have formed a 20 hamper by placing a horizontal bar 40 a short distance above the bottom plate 45. This bar is fixed to the flanges 6, preferably by welding. A plurality of short vertical bars 41 extend between the bar 40 and the front flange 16 of the 25 bottom member 15, each bar 41 being welded to these members. The hamper thus formed may conveniently receive soiled linen and the like.

Movement of the cabinet structure relative to the door is arrested by a suitable door stop when the cabinet is at right angles to the door and its interior is readily accessible. This door stop may comprise levers 45 and 46 pivoted together at 47. Lever 45 is pivoted to the door 1 by a suitable bracket 48. Lever 46 is pivoted to the cabinet by a pin 49 projected through the proper one of the holes 14 and the lever end held in place by a pin 50. Lever 45 is provided with a boss 51 which strikes against the edge of lever 46 to limit relative movement of the levers.

From the foregoing it will be seen that I have 40 provided a simple, sturdy, and yet inexpensive cabinet adapted to be mounted for either right or left swinging on a bathroom door and to be securely latched in closed position thereon. When 45 closed the cabinet is of pleasing appearance and when opened it places the articles it contains within easy reach of a person.

What I consider new and desire to have protected by Letters Patent is pointed out in the 50 appended claims.

What is claimed is:

1. A cabinet adapted to be attached to one side of a bathroom door, comprising a pair of angle members adapted to engage the stiles of the door, integral side pieces extending from said angles at an acute angle to the door, a front panel formed integrally with said side pieces and disposed parallel to the door, top and bottom plates fixed to said angles, side pieces, and panel, and having flanges adapted to engage the top and bottom rails of the door, respectively, a plurality of Z-shaped shelves fixed in said cabinet near the top thereof, each shelf having one leg extending downwardly against said panel and having another leg extending upwardly from the shelf and against said angles, a plurality of hooks fixed to the downwardly extending leg of the lower one of said shelves, a horizontal bar fixed to said angles near said bottom plate, and a plurality of vertical bars fixed to said horizontal bar and to the flange of said bottom plate to form a hamper at the bottom of said cabinet.

2. A cabinet adapted to be attached to one side of a bathroom door, comprising a pair of angle members adapted to engage the stiles of the door,

- integral side pieces extending from said angles at an acute angle to the door, a front panel formed integrally with said side pieces and disposed parallel to the door, top and bottom plates 5 fixed to said angles, side pieces and panels, and having flanges adapted to register with the top and bottom rails of the door, respectively, the stile engaging legs of said angles being pierced with holes to permit mounting hinges on either side of the cabinet, the other legs of said angles being pierced with holes to permit mounting a latch on either side of the cabinet, two relatively closely spaced Z-shaped shelf members 10 fixed in the top of said cabinet and having one leg extending downwardly against said panel and the other leg extending upwardly against said angles to form an edge on the shelf, a second pair of Z-shaped shelf members fixed in said cabinet below said first shelves and spaced apart a distance greater than the first mentioned shelves, each of said latter shelves having one leg extending downwardly against said panel and another leg extending upwardly against said angles to 15 form edges for the shelf, a plurality of hooks fixed to the downwardly extending leg of the bottom one of said shelves, a horizontal bar fixed to said angles adjacent to said bottom plate, a plurality of vertical bars fixed to said horizontal bar and to the flange of said bottom plate to form 20 a hamper at the bottom of the cabinet, said top plate containing a plurality of holes to permit mounting a door stop thereupon and adjacent to either side of the cabinet. 25
3. An open-face cabinet adapted to be attached to one side of a bathroom door, comprising a pair of angle members adapted to engage the stiles of the door, integral side pieces extending from said angles at an acute angle to the door, a front panel formed integrally with said side pieces and disposed parallel to the door, top and bottom 30
